UNITED STATES PATENT OFFICE

SAMUEL SEGAL, OF NEW YORK, N. Y., ASSIGNOR TO SEGAL AUTOMATIC TWEEZER CORPORATION, OF NEW YORK, N. Y., A CORPORATION OF NEW YORK

LIGHTER

Application filed March 5, 1928. Serial No. 259,020.

This invention relates to a lighter and aims primarily to provide a device of this character in the nature of a smoker's appliance.

5 It is an object of the invention to provide a device of this character, the parts of which will be relatively few in number and rugged and simple in construction, these parts being capable of ready assemblage to provide a 10 lighter operating over long periods of time with freedom from mechanical difficulty and which may be produced at relatively nominal figure.

A further object is that of constructing a 15 lighter in which the parts may be disassembled readily when necessary for renewal and adjustment purposes but which parts will be maintained normally against accidental displacement.

20 A still further object is that of providing such a device which will embrace a snuffer for the flame and in which the snuffer may be moved readily to inoperative position as well as to operative position.

25 With these and further objects in mind, reference is had to the attached sheet of drawings which illustrates practical embodiments of the invention, and in which:

Fig. 1 is a sectional side view of a lighter; 30 Fig. 2 is a plan view thereof;

Fig. 3 is a fragmentary side elevation taken from the side opposite to that shown in Fig. 1;

Fig. 4 is a perspective view of the snuffer 35 actuating means;

Fig. 5 is a fragmentary side elevation of a second form of lighter and showing the parts thereof in one position, and

Fig. 6 is a plan view of the device shown 40 in Fig. 5 but illustrating the parts in a different position.

In these views, the numeral 10 indicates the lighter case which may be of any desired configuration and material and which, 45 in accordance with conventional practice, may have a threaded filler opening in its base normally closed by means of a plug 11. Also extending from the upper deck of the case is a wick nozzle 12, the opening of which 50 may be covered by a snuffer 13 of any de-

sired construction, this snuffer being mounted by a lever 14 pivotally supported as at 15 upon a lug 16. The inner end of the lever is preferably cam-shaped and cooperating with the same is a spring pressed pin 17 55 which serves normally to retain the lever and cap associated therewith in either wholly raised or lowered positions. A pedestal 18 extends from the case deck and mounts a tube 19, the latter enclosing as in 60 Fig. 1 the rear end of a sparking element 20, commonly referred to as a flint, although it may be of any desired material. The rear end of the tube mounts the inner end of a screw 21 and a spring 22 is preferably interposed between the flint and this screw so as to yieldingly press the former from within the tube.

Arranged adjacent the outer end of the tube and the wick nozzle is a sparking disc 70 23, the periphery of which engages the exposed end of the flint and this disc is secured to or forms a part of a thumb wheel 24 the edge of which may be roughened to assure a proper grip being secured, it being furthermore noted that the diameter of the latter is preferably materially greater than that of the sparking disc so that the thumb will not be soiled by actuating the parts. Mounting the elements 23-24 is a shaft 25 which extends within a tube 26 forming an integral part of the case or otherwise suitably secured thereto.

In the form of device shown in Figs. 1 to 3, the diameter and thickness of the thumb 85 wheel are not such that it underlies the tube 19 but, as shown, it underlies the free end of the flint as a consequence of which it will be patent that an accidental displacement of these units is prevented unless the flint is retracted to a point at which the periphery of the thumb wheel clears the same. This will obviously be a deliberate operation and will be resorted to only when it is desired to remove the thumb wheel-sparking disc unit 90 from the case. Also, according to the present invention, it will, in fact, be unnecessary to resort to a retraction of the flint if a groove 27 is milled or otherwise formed in the periphery of the thumb wheel, this 100

groove being of a depth such that the diameter of the thumb wheel at this point is reduced to at least that of the sparking disc and the width of the groove being adequate to permit of the passage of the flint. If this expedient is resorted to, it is obvious that, an operator, by simply aligning the groove part of the thumb wheel with the flint may remove this wheel and the sparking disc free from the case. However, in normal operation, no fear will have to be felt that an accidental detachment will occur.

In the form of device shown in Figs. 5-6, the diameter of the thumb wheel is such as to extend below the tube 19 and no groove has been shown. Accordingly, the periphery of the thumb wheel must be shifted to clear the end of the tube and this is accomplished in the embodiment under consideration by providing a lever 28 which encircles the base of the pedestal 18 and has at its outer end a recess for the accommodation of the shaft of the thumb wheel-sparking disc unit. The rear end of this lever is struck up as at 29 and formed with an opening through which the shank of the screw 21 is extended, it being thus obvious that with the screw in position, the lever will be locked against shifting and the sparking disc will at all times be retained in proper position. However, when it is desired to remove the thumb wheel and sparking disc, this movement is achieved readily by simply withdrawing the screw from the tube in the manner shown in Fig. 6 after which the lever may be swung to such a position that the thumb wheel extends wholly to one side of the outer tube end whereupon the latter together with the sparking disc and the shaft mounting may be removed from the lever.

In both of the illustrated forms of the invention, it is preferred that the lever which mounts the snuffer cap at its free end be actuated by associating with the pivot 15 an operating member which may take the form shown in Fig. 4 and which includes a pair of side walls 30, a finger contact portion 31 and a transverse portion 32 which underlies the lever 14 so that by pressing 50 against the portion 31 this lever together with the wick covering structure carried thereby is virtually snapped into the position shown in Fig. 3.

From the foregoing, it will be appreciated that among others the several objects aforementioned are accomplished. It will be understood, however, that numerous changes in construction and rearrangement of the parts might be resorted to without departing 60 from the spirit of the invention as defined by the claims.

Having described my invention, what I claim as new and desire to secure by Letters Patent, is:

65 1. A lighter including a case, a thumb

wheel, a sparking disk associated therewith, means for rotatably mounting said thumb wheel and disk upon said case whereby the same may be axially shifted, and means co-operating with said disk to produce a spark, 70 said means overlying said thumb wheel to normally prevent the axial withdrawal of the latter from the case.

2. A lighter including a case, a sparking disc and thumb wheel rotatably mounted upon said case and axially movable therefrom, a tube, a pyrophoric plug associated with said tube, the end of said plug overlying said thumb wheel to normally prevent the axial withdrawal thereof from said case, the end 80 of said tube in effect terminating short of the thumb wheel edge.

3. A lighter including a case, a sparking means mounted upon said case, a thumb wheel and sparking disc rotatably supported on said case and axially movable therefrom, said sparking means overlying said thumb wheel to prevent the axial withdrawal thereof from said case and said wheel being formed with a groove to be aligned with said sparking means to permit such withdrawal.

4. A lighter including a case, a sparking disc, a thumb wheel, a shaft cooperating with said case and supporting said latter elements and a pyrophoric plug also mounted on said case and engaging the periphery of said disc and overlying said thumb wheel to prevent the axial withdrawal thereof from said case, said thumb wheel being formed with a groove to be aligned with said plug to permit withdrawal of said thumb wheel past said plug.

5. A device of the character described including a case, a wick tube extending from said case, means for directing sparks towards said wick tube, a snuffer cap cooperating with said tube a lever pivotally supported by said case and mounting said cap, a second lever also pivotally supported by said case and having one of its ends extending beyond said first named lever, its opposite end being contactible with said first named lever to elevate the latter and said cap, and said second lever being movable with respect to said first named lever.

In testimony whereof I affix my signature.

SAMUEL SEGAL.
